Des. 210,449
Patented Mar. 12, 1968

210,449

VEHICLE BODY WITH REAR WHEEL UNIT

Hilder T. Thompson, 1353 Santiago Ave.,
Santa Ana, Calif. 92701

Filed Oct. 17, 1966, Ser. No. 4,291

Term of patent 7 years

(Cl. D14—3)

FIG.1

FIG.2

FIG.3

FIG.4

FIG.5

FIGURE 1 is a side perspective view of a vehicle body with rear wheel unit showing my new design;

FIGURE 2 is a rear elevational view thereof;

FIGURE 2 is a front elevational view thereof;

FIGURE 4 is a side elevational view thereof, the opposite side being substantially identical thereto; and

FIGURE 5 is a top plan view thereof.

The elements shown in broken lines are included for illustrative purposes only.

I claim:

The ornamental design for a vehicle body with rear wheel unit, substantially as shown and described.
